UNITED STATES PATENT OFFICE

CHARLES L. TURNER, OF LOS ANGELES, CALIFORNIA, ASSIGNOR OF ONE-HALF TO
FORD W. HARRIS, OF LOS ANGELES, CALIFORNIA

VESSEL-CAPPING MACHINE

Application filed March 5, 1927. Serial No. 173,030.

My invention relates to vessel capping machines and more particularly to a machine adapted to apply flexible caps to milk bottles and the like.

5 In United States Patent No. 1,659,177, granted to me on February 14, 1928, I secured protection upon a string placed beneath the cap of a milk bottle so that the ends protrude and may be grasped to remove the cap. In 10 my co-pending application Serial No. 111,262, filed May 24, 1926, I showed a bottle capping machine which applied caps to bottles and at the same time placed a string, in the manner disclosed in said patent, under each cap 15 as it was applied.

It is the broad object of my invention to provide a novel capping machine which will perform the function of the machine shown in said co-pending application in a more 20 efficient and satisfactory manner.

In another co-pending application, Serial No. 179,605, filed March 30, 1927, I have shown a novel vessel capping machine in which a rotary cap feeder is embodied and it 25 is an object of my invention to employ said rotary cap feeder to feed a string beneath each cap fed into position beneath a capping plunger.

It is a further object of my invention to 30 provide a capping machine in which said string is wound upon said rotary feeder in a manner to draw said string from a string magazine.

Another object of my invention is to 35 provide a capping machine in which a rotary feeder carries positioning means, for string so wound, whereby successive pieces of said string are positioned respectively beneath caps taken successively by said feeder from 40 a cap magazine.

Yet another object of my invention is to 45 provide a capping machine in which said pieces are successively cut from said string as they are carried beneath said cap into the path of said capping plunger.

In many machines which handle string, the string is cut by shears which become dull rather quickly due to the inter-action of the cutting blade with another piece of metal.

50 It is an object of my invention to provide

a cutter for string, tape and the like in which the knife does not contact anything but the material to be cut.

The cutting of fibrous material is accomplished with much less energy or dulling of the cutting blade where the material is under tension. 55

It is another object of my invention to provide a cutter for string, tape and the like in which the material is placed under tension 60 and then moved into contact with a knife.

In places where the cutting of string is necessary it is often desirable that no knife or cutting edge be exposed when the cutting operation is not taking place. 65

It is therefore a further object of my invention to provide a cutter for string and the like in which the knife is normally concealed within a non-cutting member which yields to pressure of another non-cutting 70 member to bring the knife into engagement with the material to be cut.

Further objects and advantages will be made manifest in the following description and in the accompanying drawings, in which 75

Fig. 1 is a perspective view of a preferred embodiment of the capping machine of my invention with the capping plunger in its upward position relative to the body of the machine. 80

Fig. 2 is a horizontal sectional view taken on the line 2—2 of Fig. 1 showing the capping machine substantially in plan.

Fig. 3 is a fragmentary perspective view illustrating the connection between the cutter 85 slide bar and the capping plunger.

Fig. 4 is a vertical medial sectional view taken on the line 4—4 of Fig. 2.

Fig. 5 is a diagrammatic view showing the surface of the cam rotor of my invention in 90 development.

Fig. 6 is a perspective view of the cam follower screw.

Fig. 7 is a view similar to Fig. 4 showing the capping plunger in its lowermost or 95 "capping" position.

Fig. 8 is a horizontal sectional view taken on the line 8—8 of Fig. 7 and showing the rotary cap feeder of the machine in top plan.

Fig. 9 is a horizontal view looking upward 100

on the line 9—9 of Fig. 7 showing the rotary feeder in bottom plan.

Fig. 10 is a detailed vertical sectional view taken on the line 10—10 of Fig. 9.

Fig. 11 is an enlarged fragmentary perspective view illustrating a detail of the rotary feeder.

Fig. 12 is a side elevational view of the capping machine taken on the opposite side from that disclosed in Fig. 1.

Fig. 13 is a plan view of the base member of the machine.

Fig. 14 is an enlarged vertical sectional view taken on the line 14—14 of Fig. 13 and illustrating the string cutter.

Fig. 15 is an enlarged fragmentary detailed view illustrating the cutting of the string by the cutter.

Figs. 16 and 17 are vertical sectional views taken on correspondingly numbered lines of Fig. 4.

The capping machine 20 is mounted upon a capping machine reciprocator 21 which is reciprocated vertically over a fixed path by a suitable power mechanism, not shown. As the reciprocator 21 moves up and down, the capping machine 20 is adapted to move with the reciprocator and does not function unless a bottle 22 is placed in the proper position therebeneath. When a bottle 22 is properly placed beneath the capping machine, the machine moves into contact with a bead 23 surrounding the mouth of the bottle and applies a cap 24 by inserting it in the mouth of the bottle. As the cap 24 is applied, a string 25 is placed by the machine 20 between the bottle and the cap, as clearly shown in Fig. 1. The capping machine 20 may be described as follows:

A slide frame 30 has a vertical plate 31 which is secured to the reciprocator 21 as by cap screws 32. Formed at the upper end of the plate 31 is a projection 33 which has a suitable vertical aperture 34. Extending from the lower end of the plate 31 is a guide-yoke 36 which provides opposed arms 37 and 38 in which guideways 39 and 40 are formed which are diametrically opposed to each other upon opposite sides of the vertical axis of the aperture 34. A capping plunger 44, as shown in Figs. 1 and 4, includes a square plunger body 45 having polished side faces, from which body a cylindrical neck 47 extends downward and receives at its lower end a capping plunger head 48. A plunger spring stem 52 extends upward from the square body 45 in axial alignment with the body 45 and the neck 47. The stem 52 has a pin hole 53 at its upper end and is adapted to receive a compression spring 55. The upper end of the stem 52 is inserted upward through the hole 34 so as to compress the spring 55, and a suitable pin 56 is then inserted in the hole 53 to retain the stem 52 against withdrawal from the hole 34.

The square body 45 has a recess 60 formed in the inner side of the lower end thereof and which is adapted to receive a stop block 61. The stop block 61 has a cutter actuating arm 62 formed integrally therewith, as clearly shown in Fig. 3, for a purpose to be described later. The square plunger body 45 and the stop block 61 are provided with aligned openings 63 and 64. The hole 64 is threaded so as to threadedly receive a cam follower screw 65 which is adapted to pass freely through the hole 63 without engagement with the walls thereof. The cam follower screw 65 is slotted at 66 for manipulation by a screw driver, and has a cam follower pin 67 provided upon its opposite end eccentric with the axis of the screw, as clearly shown in Fig. 6. The screw 65 is adapted to be inserted through the hole 63 and screwed in the hole 64 until the cam follower pin 67 projects beyond the inner surface of the stop block 61, as shown in Fig. 4. A nut 68 is then adapted to be screwed upon the outer end of the screw 65 and tightened against the outer face of the square plunger body 45. When the nut 68 is thus tightened to secure the screw in place, the cam follower pin 67 may be disposed at an adjustable position relative to the vertical medial plane of the machine upon which the sectional view shown in Fig. 4 is taken. The purpose of this adjustment will be described later.

The capping machine 20 has a body 70 which includes a main casting 71 and a base member 72 which are associated in a manner to be described later. The casting 71 is best illustrated in Figs. 1, 2, 3, and 12 and includes an upper floor 75, an intermediate floor 76, and a lower floor 77. These floors are connected at their side portions by main slide bars 79 and 80 which accurately fit the diametrically opposed guideways 39 and 40. At the opposite end of the upper floor 75 from the connection of this floor with the slide bars 79 and 80 a cap magazine receptacle 82 is formed which is substantially cylindrical in shape and has a cylindrical cavity 83 in which a tubular paper magazine 84 of bottle caps 24 is adapted to fit. The cylindrical cavity 83 extends downward to a magazine tube seat 85 from which a cap conveying bore 86 extends downward and inward into communication with the lower face of the lower floor 77. A peek slot 87 is formed in the wall of the receptacle 82 while a peek hole 88 is provided in the wall of the bore 86. These peek holes are for the purpose of obtaining information as to the number of caps remaining in the machine.

The intermediate floor 76 is formed integrally at one end with the magazine receptacle 82 and the other end is connected with the lower floor 77 by a plunger head cylinder 90. The cylinder 90 has a bore 91 of sufficient diameter that the plunger head 48 may re-

ciprocate vertically therein, the bore 91 terminating at the lower surface of the intermediate floor 76 and opening downward through the lower floor 77. A hole 90^a is formed in the cylinder 90 through which to observe the action of the plunger head 48 in the bore 91. The bore 91 is disposed on the axis of the capping plunger 44 and a hole 92 in the intermediate floor 76 is adapted to slidably receive the plunger neck 47 so that the neck 47 may actuate the plunger head 48 in the cylinder bore 91. A plunger guide recess 95 is formed in the opposite end of the upper floor 75 from where this connects with the magazine receptacle 82, the recess 95 slidably fitting three side faces of the square plunger body 45. A guide block 96 is secured by screws to this end of the upper floor 75 so as to slidably engage a fourth side face of the square plunger body 45. The square plunger body thus slidably engages the upper floor 75 but is prevented from rotation relative to the body 70. The block 96 has a neck 98 extending arcuately away from the machine body 70, the neck 98 having a cylindrical string magazine shell 100 formed thereon. The shell 100 has a wall 101 closing one end thereof, the wall 101 having a central, apertured boss 102 provided on the outer surface thereof. The opposite end of the shell 100 from the wall 101 is open and is adapted to receive a cap 103. The cap 103 is provided with a knob 104 for the manipulation of the same, and a stem 105 which is of sufficient length to pass through a ball of string 106 and, extending the length of the shell 100, projects into the apertured boss 102. The shell 100 has an opening 108 through which a string 109 is adapted to be drawn from the ball 106. A hole 110 is formed downward through the main slide bar 80, the string 109 being adapted to be drawn downward through the hole 110 and out from the lower end thereof as shown in Fig. 1.

The casting 71 is solid between the cylinder 90 and the cap conveying bore 86 and a cam roller stem bore 115 is formed in the casting to extend between the upper face of the intermediate floor 76 and the lower face of the lower floor 77 substantially parallel with the axis of the capping plunger 44. The upper end of the bore 115 has an enlarged counterbore 116. The upper floor 75 has a bore 117 axially aligned with and substantially of the same size as the counterbore 116 and which extends entirely through the upper floor 75.

A cam rotor 120 has a substantially cylindrical cam body 121 and a rotor stem 122 extending axially from the lower end of the body and a pin 123 extending axially from the upper end thereof. The rotor body 121 is of slightly less diameter than the opening 117 in the upper floor 75 and when the rotor 120 is inserted downward through the open-

ing 117, the stem 122 is journalled in the bore 115. Before the rotor is thus inserted into the opening 117 an anti-friction thrust bearing 125 is placed in the counterbore 116 and when the cam rotor is in place it is supported upon this bearing. An anti-friction bearing 126 is adapted to fit the pin 123 of the rotor 120 and be disposed in the upper portion of the opening 117, as clearly shown in Fig. 4. A bearing cap 127 is adapted to be secured against the upper face of the upper floor 75 by screws 128 in a manner to position the upper bearing 126 so that the rotor 120 is accurately held against axial movement relative to the capping machine body 70. Cam grooves 130 are provided in the outer surface of the cam roller 120 and are of such width as to receive the cam follower pin 67, as shown in Fig. 4. These grooves provide cam surfaces, the function of which will be described later.

The lower end 131 of the rotor stem 122, where this projects below the lower floor 77, is polygonal in cross-section, this in the present instance being triangular.

On the side of the capping machine which is visible in Fig. 12, the upper floor 75 is provided with a projection 133 which has a recess 134 formed therein. The material of the casting 71 extends upward from the intermediate floor 76 just below the projection 133 to form a wall 135 having a shoulder 136 provided with a recess 137 which is disposed vertically below and in alignment with the recess 134. Guide blocks 138 and 140 are secured by machine screws 141 to the projection 133 and the shoulder 136 respectively. The guide blocks 138 and 140 have recesses 143 which cooperate with the recesses 134 and 137 to form slideways in which a cutter slide bar 144 is slidably received. The slide bar 144 has a notch 146 into which the cutter actuating arm 62 extends so that any vertical movement of the plunger 44 is transmitted to the cutter slide bar 144. The cutter slide bar has a foot 147 provided upon its lower end, from the outer end of which a gripping member 148 extends downward. The gripping member 148 has a slot 149 formed centrally upward in its lower end and the lower end of the member 148 is beveled upward on opposite sides of the slot 149 to provide converging faces 150. The faces 150 meet the faces of the slot 149 to form contacting edges 151.

The lower floor 77 is provided with dowel pin holes 152 and 153 on the medial vertical sectional plane of the view shown in Fig. 4 near the ends of the lower floor. On opposite sides of the dowel pin hole 152 are formed threaded holes 155. On each side of the dowel pin hole 153 is formed a bore 156. The base member 72 is of substantially the same length as the lower floor 77 and has lower walls 159 and 160 extending upward

from its opposite ends. The walls 159 and 160 are of the same height and dowel pins 161 and 162 are centrally provided to project upward from these walls so as to be received in the dowel pin holes 152 and 153 respectively in order to accurately position the base member 72 relative to the body casting 71. Counterbored holes 165 are formed in the base member 72 so as to be aligned with the holes 155 of the lower floor 77 and screws 166 are adapted to be extended upward in the holes 165 and screw into the threaded holes 155 so that the heads of the screws 166 are received into the counterbored portions 15 of the holes 165, as clearly shown in Fig. 16.

Threaded holes 167 are adapted to be formed in the base member 72 on opposite sides of the dowel pin 162 so as to be aligned with the holes 156 formed in the lower floor 77. A string guiding eye 170 is formed at the end of a strap 171 having screw holes through which cap screws 172 are adapted to pass into the holes 156 and be threadedly received into the holes 167, as clearly shown in Fig. 17.

When the base member 72 is thus secured in place upon the body casting 71, a finger hole 175 which is formed in the base member 72 is disposed axially beneath the lower mouth of the bore 86. A cylindrical recess 176 is formed in the upper face of the base member 72 in axial alignment with the cam rotor 120. A cylindrical plunger mouth 177 extends vertically through the base member 72 in axial alignment with the plunger 44. The lower portion of this mouth 177 is counterbored to form a frusto-conical bottle guiding mouth 178.

A recess 180 is formed in the upper face of the base member 72, as clearly shown in Figs. 13 and 14. The recess 180 is joined by a slot 181 at one end thereof with the plunger mouth 177. A leaf spring 182 having substantially the same outline as the recess 180 is disposed therein and has an end 183 thereof secured against the bottom surface 184 of the recess 180 by a cap screw 185 which is threadedly received in a suitable hole 186 formed in the base member 72. The spring 182 is bent upward from the portion 183 and is then rebent so that the opposite end portion 187 is adapted, when the spring is slightly compressed downward, as shown in Fig. 14, to be disposed with its upper face on a level with the upper face of the base member 72. A boss 190 is formed upon the lower face of the spring 182 near the center thereof, this boss being provided with a threaded aperture 191, and a counterbored hole 192 is formed upward in the base member 72 and a machine screw 193 is inserted upward into the hole 192 and screwed into the threaded aperture 191 of the spring 182. As shown in Fig. 14, the screw 193 thus limits the upward movement 65 of the spring 182, but permits this spring to

be depressed downward, as shown by the dotted lines 195.

A knife blade 196 is provided upon the end of a plate 197 so that when the plate 197 is rigidly secured against the bottom surface 184 of the slot 180 by machine screws 199, as shown in Fig. 14, the edge of the knife blade 196 will be disposed opposite the center axis of and just beneath a slot 200 which is diagonally formed in the free end of the spring 182. When the spring 182 is depressed into the position 195, the edge of the knife blade 196 projects upward through the slot 200 without touching the spring 182.

The slot 149 in the string-gripping member 148 is narrower than the slot 200 in the spring 182, and the string-gripping member 148 is adapted to move downward so that the contacting edges 151 pass between the edges 210 of the slot 200, as shown in Fig. 15. If a string is disposed across the path of the string-gripping member 148, it will be gripped, as shown in Fig. 15, between the faces 150 and the edges 210 of the slot 200. The portion of the string disposed between the edges 151 will be held taut. Due to the slot 149 being aligned with the slot 200, it is also in alignment with the knife blade 196 and as the string-gripping member 148 continues downward from the position in which it is shown in Fig. 15, the knife blade 196 extends upward into the slot 149, easily severing the string.

When the base member 72 is assembled upon the lower floor 77, the lower floor 77 and the upper face of the base member 72 are parallel and form a flat space 212 in which a rotary feeder 213 is disposed. The rotary feeder 213 is in the form of a disc which has a central polygonal opening 214 which fits the polygonal end 131 of the rotor stem 132. The feeder 213 is then held in place upon the lower end of the rotor stem 122 by a washer 215 and a screw 216 which extends upward through the washer and is screwed into a threaded hole provided centrally in the lower end 131 of the stem 122. The recess 176 in the upper face of the base member 72 provides a space in which the washer 215 is disposed when the machine is assembled. The rotary feeder 213 when thus mounted upon the lower end of the rotor stem 122 has opposite portions thereof disposed adjacent to the lower end of the cap bore 86 and to the plunger head bore 91 respectively. The upper face of the feeder 213 makes a sliding fit with the lower face of the lower floor 77.

A series of holes 220 are formed vertically through the feeder disc 213, these being uniformly slightly less in diameter than the diameter of the caps 24 and are symmetrically arranged about the center of the feeder 213. In the present instance, there are three of the holes 220. Counterbores 221 are formed in the upper end of the holes 220 having the

same diameter and the same depth as one of the caps 24. The holes 220 are formed at such a distance from the axis of the feeder 213 that each is successively disposed in alignment with the cap bore 86 and the plunger bore 91. As each of these holes comes opposite the cap conveying bore 86, a cap drops downward into the counterbore 221 thereof and upon rotation of the feeder is carried through an angle of 180°, into alignment with the plunger bore 91. Smaller holes 224 are formed vertically through the feeder 213, and are symmetrically disposed about the center of the feeder equidistant from the holes 220. The lower portion of the feeder 213 is machined away near the periphery thereof to form a peripheral portion 225 which is thinner than the central feeder portion 226 which remains a maximum thickness and makes a sliding fit with the upper face of the base member 72. The central portion 226 is turned away adjacent to the holes 220 for a purpose to be described later. In a given direction from each of the holes 224, the central thicker portion 226 of the feeder 213 extends outward between that hole 224 and an adjacent hole 220 to form a shoulder 227. On the opposite side of each hole 224 the thickened feeder portion 226 is cut away closer to the center of the feeder to form a spring finger abutting shoulder 228. Spring fingers 230 have downward curved outer end portions 231 and their opposite ends 232 are square so as to be adapted to abut against the shoulders 228. A washer 233 is placed between the lower face 234 of the peripheral feeder portion 225 and the square end 232 of the finger 230, and a machine screw 236 is extended through the finger 230 and the washer 233, and is screwed into a suitable threaded hole 237 formed in the feeder 213, as clearly shown in Fig. 10. The washers 233 are of such thickness that a string of suitable diameter will be yieldably gripped when placed between a finger 230 and the surface 234. As clearly shown in Figs. 1, 2, 8 and 9, the string 109 which is unwound from the ball 106 in the string magazine 100 is adapted to be drawn through the hole 110 and the eye 170 and be wound about the shoulders 227 and the washers 233 next to the surface 234 of the feeder 213. In order to thus wind the string 109 upon the feeder 213, the feeder is adapted to rotate in the direction of the arrow 240. When the string 109 is thus wound upon the feeder 213, portions 241 of this string are disposed so that one of these portions is positioned diametrically across the lower end of each of the holes 220. Portions 242 of the string 109, which are disposed between the portions 241, extend diametrically across the lower end of each of the holes 224.

The operation of my machine is as follows:

As before stated the capping function of the machine does not take place unless a bottle 22 is suitably positioned therebeneath as the machine descends downward with the vertical reciprocating movement of the machine reciprocator 21. The body 70 of the machine is vertically slideable relative to the slide-frame 30 and the capping plunger 44, between the downward position of the body, where it is shown in Figs. 1, 3, 4, and 7, and the upward position of the body which is shown in Figs. 7 and 12. The body 70 remains in its downward position excepting when the bottle 22 is so placed that the annular bead 23 thereof engages the bottle guiding-mouth 178 and stops the body's downward movement. When this occurs the plunger 44 continues downward under the yieldable pressure of the spring 55. This relative movement between the plunger and the rotor 120, mounted against axial displacement on the body 70, operates the rotary feeder 213 in the following manner:

When the capper body is in its lower position, the cam follower-pin 67 has the position 250 shown in full lines in Fig. 5. At this time one of the holes 220 in the rotary feeder 213 is opposite the cap bore 86 and has here received a cap in its counterbore. Another of the holes 220 is empty and is disposed so that a 120° rotation of the feeder in the direction of arrow 240 will bring that hole into alignment with the cap conveying bore 86. The third hole 220 carries a cap in its counterbore and is disposed so that a 60° rotation of the feeder in the direction of the arrow 240 will bring the third hole into alignment with the plunger head bore 91.

The cam grooves 130, as shown in development in Fig. 5, constitute a single-cycle cam multiplied three times. In each cycle the cam follower-pin 67 is adapted to move from the position 250 downward to the position 251 and return to a position 252, which corresponds to the position 250 for the next succeeding cycle. Considering the cycle to commence with the contact of the bottle-guiding-mouth 178 with the bottle 22 and the consequent beginning of a downward movement by the plunger 44, relative to the body 70, the cam follower-pin 67 here leaves the position 250 and contacts a cam slot surface 253 which causes the cam rotor 120 to rotate until the follower-pin 67 has reached the position 254 where it is disposed between the walls of a cam slot 255 which is in vertical parallelism with the axis of the rotor 120. In moving from the position 250 to the position 254, the cam follower-pin 67 has caused the feeder to rotate 60°. This brings the third mentioned of the openings 220, charged with a cap, into alignment with the plunger head bore 91. As the plunger continues downward after the cam follower-pin 67 has reached the position 254, the feeder 213 is held in position so that

the plunger head 48 will engage the cap 24 disposed in its path and will pass through the hole 220 in which this cap rests to the position in which it is shown in Fig. 7, where the plunger forces the cap 24 into the mouth of the bottle 22. Bottles 22 are so positioned vertically that the plunger 44 arrives at capping position when the machine reciprocator 21 reaches the lower end of its downward movement. The extreme downward position 10 of the plunger head 48 relative to the body 70 is determined by contact of the stop block 61 against the upper surface of the intermediate floor 78. As the reciprocator 21 returns upward the plunger 44 is raised from the position in which it is shown in Fig. 7 and the cam follower-pin 67 rises from the position 251 to the position 258 in which it engages the cam surface 259. During the final 15 upward portion of the movement of the plunger 44 relative to the body 70, the cam follower-pin 67 moves from the position 258 to the position 252. This movement of the cam follower-pin 67 causes another 60° rotation of the rotor 120 and the rotor feeder 213. This 60° rotation added to the 60° rotation which took place on the downward stroke of the plunger 44 brings the empty 20 hole 220, first referred to as such above, into alignment with the cap bore 86 so that this hole receives a cap. As before mentioned, the cam surfaces 253 and 259 and the cam slot 255 are triplicated about the surfaces of the rotor 120 so that for each downward and upward movement of the plunger 44 the rotary feeder 213 is rotated 120° in the direction of the arrow 240 and a cap is fed into the path of the plunger head 48 in the manner above described.

40 As the plunger 44 moves downward in a capping movement, it is thus seen that the feeder 213 is moved during the first portion of the downward movement of the plunger into the position in which the feeder is shown in Figs. 8 and 9. Whenever the feeder 213 is in this position one of the holes 224 is disposed directly beneath the string-gripping member 148 so that as this moves downward with the plunger 44 it will pass directly 45 through this hole 224 and into the relation with the cutter spring 182 in which it is shown in Figs. 12 and 15. As shown in Figs. 8 and 9, the extreme end portion 242 of the string 109 has its extremity 260 held beneath one of the yieldable fingers 230 so that the piece of string 241 is extended across beneath the cap that lies in the path of the plunger head. As the plunger moves into engagement with the cap it forces the extreme end 50 piece 241 downward with the cap toward the mouth of the bottle 22. Concurrent with the final downward cap movement of the plunger head 248, the string-gripping member 148 moves downward through the position shown in Fig. 15 which results in the

cutting of the extreme end piece 241 from the string at 262, as shown in Fig. 9. This extreme end piece of string is now held only by the gripping of its extremity 260 beneath one of the fingers 230. The friction with which this extremity 260 is held by the single finger 230 is insufficient to prevent its being withdrawn from beneath this finger 230 when the capping machine 20 rises from engagement with the bottle 22. Thus each piece of string 241 is placed beneath a cap when this is being applied to the bottle and is cut off so that the friction with which the string is engaged between the cap and the bottle will easily draw this piece of string from under a finger 230 against the slight yieldable pressure with which it is held by this finger.

An adjustment of the screw 65 changing the position of the cam follower-pin projecting eccentrically therefrom, causes a change in the position of the rotary feeder 213 for a given vertical relation between the plunger 44 and the machine body 70. This adjustment makes it possible to determine accurately whether the feeder 213 will be so rotated by engagement of the cam rotor 120 by the follower-pin 67 that a hole 220 will be in correct axial alignment with the plunger head 48 during the lower portions of its downward and upward movements.

The central thicker portion of the rotary feeder 213 is turned away adjacent to the holes 220 to permit each cap to expand equally in all directions as it leaves the lower mouth of a hole 220 under pressure of the plunger head 48. If the cap were permitted to expand in one direction and not in the opposite direction, it would tend to throw itself out of vertical alignment with the plunger head 48.

I claim as my invention:

1. In a vessel capping machine, the combination of: a magazine for storing caps; a capping member movable toward a vessel for capping the same; a rotatable member for feeding a cap from said magazine into position between said capping member and said vessel; means upon said rotatable member for extending a string between said cap and said vessel; and means for cutting a piece from said string.

2. In a vessel capping machine, the combination of: a magazine for storing caps; a capping member movable toward a vessel for capping the same; a rotatable member for feeding a cap from said magazine into position between said capping member and said vessel; means upon said rotatable member for extending a string between said cap and said vessel; and means for cutting a piece from said string, said rotatable member being rotated and said cutting means actuated by said movement of said capping member.

3. In a vessel capping machine, the combi-

5 nation of: a magazine for storing caps; a plunger reciprocable in a given path; a rotatable feeder for receiving caps from said magazine and for carrying them successively into said path; means upon said feeder to engage and draw a string into such position relative to said feeder that pieces of said string are disposed beneath said caps received by said feeder; and means for cutting off each 10 of said pieces from said string.

15 4. In a vessel capping machine, the combination of: a magazine for storing caps; a plunger reciprocable in a given path; a rotatable feeder for receiving caps from said magazine and for carrying them successively into said path; means upon said feeder to engage and draw a string into such position relative to said feeder that pieces of said string are disposed beneath said caps received 20 by said feeder; and means for cutting off each of said pieces from said string when it is disposed, with the cap above it, in said plunger path.

25 5. In a vessel capping machine, the combination of: a magazine for storing caps; a plunger reciprocable in a given path; a rotatable feeder for receiving caps from said magazine and for carrying them successively into said path; means upon said feeder to engage and draw a string into such position relative to said feeder that pieces of said string are disposed beneath said caps received 30 by said feeder; and means for cutting off each of said pieces from said string, said cutting means being actuated by said plunger.

35 6. In a vessel capping machine, the combination of: a magazine for storing caps; a plunger reciprocable in a given path; a rotatable feeder for receiving caps from said magazine and for carrying them successively into said path; means upon said feeder to engage and draw a string into such position relative to said feeder that pieces of said string are disposed beneath said caps received 40 by said feeder; and means for cutting off each of said pieces from said string after it has been so disposed, with the cap above it, in said plunger path, said cutting means being actuated by said plunger.

45 7. In a vessel capping machine, the combination of: a magazine for storing caps; a plunger reciprocable in a given path; a rotatable feeder for receiving caps from said magazine and for carrying them successively into said path; means upon said feeder to engage and draw a string into such position relative to said feeder that pieces of said string are disposed beneath said caps received 50 by said feeder; and means for cutting off each of said pieces from said string when it is disposed, with the cap above it, in said plunger path, said cutting means being actuated by said plunger substantially concurrently with engagement of said cap by said

plunger in a capping stroke of said reciprocation.

80 8. In a vessel capping machine, the combination of: a magazine for storing caps; a plunger reciprocable in a given path; a rotatable feeder for receiving caps from said magazine and for carrying them successively into said path; means upon said feeder to engage and draw a string into such position relative to said feeder that pieces of said string are disposed beneath said caps received 75 by said feeder; string-gripping members including a stationary member and a travelling member adapted to press said string against said stationary member; and a cutting member adapted to cut said string upon a relative movement between said cutting member and said gripping members when the latter are gripping said string.

85 9. In a vessel capping machine, the combination of: a magazine for storing caps; a plunger reciprocable in a given path; a rotatable feeder for receiving caps from said magazine and for carrying them successively into said path; means upon said feeder to engage and draw a string into such position relative to said feeder that pieces of said string are disposed beneath said caps received 90 by said feeder; string-gripping members including a stationary member and a travelling member connected to said plunger and adapted to press said string against said stationary member upon a given movement of said plunger; and a cutting member adapted to cut said string upon a relative movement between said cutting member and said gripping members when the latter are gripping said string.

95 10. In a vessel capping machine, the combination of: a magazine for storing caps; a plunger reciprocable in a given path; a rotatable feeder for receiving caps from said magazine and for carrying them successively into said path; means for rotating said feeder by the reciprocation of said plunger; means upon said feeder to engage and draw a string into such position relative to said feeder that pieces of said string are disposed beneath said caps received by said feeder; and means for cutting off each of said pieces from said 105 string.

110 11. In a vessel capping machine, the combination of: a magazine for storing caps; a plunger reciprocable in a given path; a rotatable feeder for receiving caps from said magazine and for carrying them successively into said path; means for rotating said feeder by the reciprocation of said plunger; means upon said feeder to engage and draw a string into such position relative to said feeder that pieces of said string are disposed beneath said caps received by said feeder; and means for cutting off each of said pieces from said string, said cutting means being actuated by said plunger substantially concurrently 115 120 125 130

with the engagement of a cap by said plunger in a capping stroke of said reciprocation.

12. In a vessel capping machine, the combination of: a magazine for storing caps; a plunger reciprocable in a given path; a rotatable feeder for receiving caps from said magazine and for carrying them successively into said path; means for rotating said feeder by the reciprocation of said plunger; means upon said feeder to engage and draw a string into such position relative to said feeder that pieces of said string are disposed beneath said caps received by said feeder; and means for cutting off each of said pieces from said string when it is disposed, with the cap above it, in said plunger path, said cutting means being actuated by said plunger substantially concurrently with engagement of said cap by said plunger in a capping stroke of said reciprocation.

13. In a vessel capping machine, the combination of: a magazine for storing caps; a plunger reciprocable in a given path; a rotatable feeder for receiving caps from said magazine and for carrying them successively into said path; means for rotating said feeder by the reciprocation of said plunger; means upon said feeder to engage and draw a string into such position relative to said feeder that pieces of said string are disposed beneath said caps received by said feeder; string-gripping members including a stationary member and a travelling member connected to said plunger and operable to press said string against said stationary member upon a given movement of said plunger; and a cutting member for cutting said string upon a relative movement between said cutting member and said gripping members when the latter are gripping said string.

14. In a vessel capping machine, the combination of: a frame; a cap magazine on said frame; a plunger slidably mounted on said frame to reciprocate in a given path, there being a space in said frame; a cap feeder rotatably mounted upon said frame in said space; means for connecting said feeder to said plunger whereby the reciprocation of the plunger rotates the feeder to feed caps into said path; and means provided upon said feeder to place a piece of string beneath each of said caps fed into said path.

15. In a vessel capping machine, the combination of: a frame; a cap magazine on said frame; a plunger slidably mounted on said frame to reciprocate in a given path, there being a space in said frame; a cap feeder rotatably mounted upon said frame in said space; means for connecting said feeder to said plunger whereby the reciprocation of the plunger rotates the feeder to feed caps into said path; means provided upon said feeder to place a piece of string beneath each of said caps fed into said path; and cutting means including a string-gripping member

provided on said frame beneath said feeder and a string-gripping member slidably mounted on said frame and reciprocated by said plunger, and a knife provided on said machine so as to be movable relative to one of said gripping members, said gripping members being adapted to hold said string tightly at two points, and said knife being adapted to contact said string between said points.

16. In a vessel capping machine, the combination of: a magazine for storing caps; a capping member adapted to move toward a vessel for capping the same; a rotatable member for feeding a cap from said magazine into position between said capping member and said vessel; means for actuating said rotatable member; means for holding a string; means for extending a string between said cap and said vessel; and means for cutting a piece from said string.

17. In a vessel capping machine, the combination of: a magazine for storing caps; a capping member adapted to move toward a vessel for capping the same; a rotatable member for feeding a cap from said magazine into position between said capping member and said vessel; means for holding a string; means for extending a string between said cap and said vessel; and means for cutting a piece from said string.

18. In a vessel capping machine, the combination of: a magazine for storing caps; a capping member adapted to move toward a vessel for capping the same; a rotatable member for feeding a cap from said magazine into position between said capping member and said vessel; a string magazine; means for drawing a string from said magazine to said rotatable member between said cap and vessel; and means for cutting a piece from said string.

19. In a vessel capping machine, the combination of: a magazine for storing caps; a capping member adapted to move toward a vessel to be capped; a rotatable member for feeding a cap from said magazine between said capping member and vessel; a string magazine; means for successively positioning pieces of said string beneath caps taken successively by said feeding member from said cap storage magazine; and means for cutting a piece from said string.

20. The combination as defined in claim 18 in which the string cutting means comprises a gripping member and a spring member which yields to pressure of said gripping member to bring the string cutting means into engagement with the string to be cut.

21. The combination as defined in claim 1 in which the rotatable cap feeding member is provided with means for changing the position thereof.

22. The combination as defined in claim 1 in which said rotatable cap feeding member

is provided with a recess to allow each cap to expand equally in all directions as it leaves the rotatable member under pressure of the capping member.

5 23. The combination as defined in claim 14 in which the rotatable cap feeder is provided with means for changing the position thereof for a given vertical relation between the plunger and the frame.

10 24. The combination as defined in claim 15 in which the cap feeder is provided with means for changing its position for a given vertical relation between the plunger and the frame.

15 25. The combination as defined in claim 14 in which said cap feeder is formed with a series of cap openings and wherein means is provided for positioning a cap opening of the cap feeder in axial alignment with the

20 plunger.

25 26. The combination as defined in claim 1 in which said rotatable member is formed with a series of cap receiving openings and wherein means is provided for positioning a cap receiving opening of the rotatable member in axial alignment with the capping member.

30 27. In a vessel capping machine, the combination of: a magazine for storing caps; a plunger reciprocable in a given path; a rotatable feeder formed with a series of openings for receiving caps from said magazine and for carrying them successively into said path; means for positioning a cap receiving opening in axial alignment with said plunger; means upon said feeder to engage and draw a string into such position relative to said feeder that pieces of said string are disposed beneath said caps received by said feeder; and means for cutting off each of said pieces from said string after it has been so disposed, with the cap above it, in said plunger path.

35 40 In testimony whereof, I have hereunto set my hand at Los Angeles, California, this 26th day of February, 1927.

CHARLES L. TURNER.
